T. PFISTER.
MOUNTING OF ENTOMOLOGICAL SPECIMENS.
APPLICATION FILED MAR. 27, 1916.

1,209,487.

Patented Dec. 19, 1916.

UNITED STATES PATENT OFFICE.

THEOPHIL PFISTER, OF NEW YORK, N. Y.

MOUNTING OF ENTOMOLOGICAL SPECIMENS.

1,209,487.

Specification of Letters Patent. Patented Dec. 19, 1916.

Application filed March 27, 1916. Serial No. 86,886.

To all whom it may concern:

Be it known that I, THEOPHIL PFISTER, a citizen of the United States, and a resident of the city and State of New York, have invented certain Improvements in the Mounting of Entomological Specimens, of which the following is a specification.

This invention relates to certain improvements in the mounting of entomological specimens such, for example, as the lepidoptera and various other winged insects, as butterflies, moths, and the like, and has for its object to provide a mounting for such specimens of a simple and comparatively inexpensive nature, presenting certain features of novelty and improvement whereby the liability of breakage or injury due to the delicate and essentially fragile character of the specimens, more especially when dried, is overcome, and the specimens are reinforced and strengthened, without detracting from their ornamental appearance, to such an extent as to permit of being readily handled in order that they may be adapted for various uses such, for example, as for table ornaments and for other decorative purposes.

The invention consists in certain novel features of the construction, and combinations and arrangements of the several parts of the improved mountings, whereby the same are rendered simple, comparatively inexpensive, and capable of ready and convenient application to the specimens to strengthen and reinforce the same against injury or damage due to ordinary handling, all as will be hereinafter fully set forth.

The novel features of the invention will be carefully defined in the claims.

In order that my improvements may be the better understood, I will now proceed to describe my invention with reference to the accompanying drawings, wherein—

Figure 1 is a perspective view illustrating an embodiment of my improved mounting applied to a moth or butterfly; Fig. 2 is an enlarged sectional view taken through the specimen showing certain features of the improved mounting which will be herein-after explained; Fig. 3 is a view illustrating the application of the mounting to a wing of the insect to be reinforced, and Fig. 4 is a sectional view somewhat similar to Fig. 2, but illustrating a modified arrangement of the wing reinforcement which will be hereinafter described.

In these views I have shown my improved mounting applied to a moth or butterfly, for strengthening or reinforcing the delicate and fragile wing structure thereof, but although my invention presents important advantages for application to specimens of this kind, by reason of the highly ornamental appearance of the mounted specimens, and of the extremely fragile character of their wing scales which renders them particularly difficult of handling without injury, I do not desire to be understood as limiting myself to this or any other special application of my improvements, since it will be apparent that the improved mounting may be applied for use in connection with many other specimens such, for example, as the neuroptera, with very good results.

In carrying out my invention, in the embodiment herein illustrated, I first detach the wings of the specimen, and after laying them flat upon some suitable surface, inner or under side uppermost, I apply a coating of some suitable cement or adhesive as water glass, varnish, glue or the like to said inner or under surfaces of the wings, after which I apply a sheet of some suitable reinforcing material, as indicated at 1 in Fig. 3, upon the prepared adhesive surfaces of the wings, pressing the same securely in place upon the reinforcing material, as indicated at 2 in said figure.

Various sheet materials may be used for the wing reinforcements as, for example, silk and various other textile fabrics, crêpe de chine and other finely woven materials being well adapted for this purpose by reason of the strength and durability imparted by them to the delicate and fragile wing structure without rendering the reinforcements themselves obtrusively apparent. In lieu of the employment of sheet reinforcements, the wing reinforcements may be produced, if desired, by the application of some tough adhesive to the wings as, for example, collodion or a solution of celluloid in amyl acetate applied upon the wings of the specimen in such a manner as to form a tough reinforcing coating thereon.

Where the reinforcements are to be applied to butterflies and other lepidoptera, it will ordinarily be necessary or preferable first to remove the wing scales from the under or inner surfaces of the wings, as these ordinarily tend to prevent the adherence of

the reinforcement to the wings. This may be accomplished by carefully brushing the scales from the inner or under surfaces of the wings by means of a fine brush.

5 After the application of the reinforcing material to the wings, assuming that sheet material be employed for this purpose, I prefer to cut away said material along the outer margins or edges of the wings, as indicated in Fig. 3, leaving a thin reinforcement 3 secured upon the under or inner surface of each wing and conforming substantially with the natural outline of the same, as clearly shown in Figs. 1 and 2 of the drawings, so as to strengthen the wing very greatly in order to render it capable of being subjected to ordinary handling without material liability of being broken or injured and also without appreciably detracting 10 from the appearance of the natural wing, since the reinforcement will be invisible at the outer surface where the more vivid coloring is present precisely as in nature. If desired, the reinforcement may also be transparent, or colored or ornamented in simulation of the natural wing markings. Where desired, also, the wings of two similar specimens may be employed in conjunction with a single reinforcement interposed between 15 them in order that the natural wing markings may be displayed at opposite surfaces of each wing of the mounted specimen.

After the preparation of the wings as hereinbefore described, I apply them to the 20 body of the specimen by attachment in any preferred manner at the opposite lateral sides thereof. For ordinary decorative uses, it may be preferable, on account of the fragile and brittle character of the natural body, to substitute therefor an artificial body made up of lower and upper members 4 and 5 of similar outline secured one above the other by means of cement or glue, the edge portions of the prepared and reinforced wings 25 being glued or cemented in place between the lateral edge portions of said members in order to afford a secure attachment of the wings with said body. If desired, however, the natural body may be employed in a similar manner, or the reinforced wings may be secured to the opposite sides thereof in any preferred way. It will usually be found desirable to arrange the parts so that the reinforcement of each wing has direct connection 30 with the body and for this purpose, the reinforcing material may be trimmed in such a manner as to leave a slight extension of the reinforcement at the edge of the wing in proximity to the body, as indicated in 35 dotted lines at 6 in Fig. 3 of the drawings, the extension thus provided affording a secure and strong attachment of the wing to the body of the specimen.

In Fig. 2 I have shown the body of the 40 mounted specimen provided with an inserted

thin metal or other reinforcement 7, capable of being bent between the fingers in order that the wings of the specimen may be thrown at different angles to the body as may be desired. In packing the specimens for shipment, they will ordinarily be pressed in flat form, and it is desirable in many instances to raise the wings at angles as indicated in Fig. 1, to facilitate which the plate or reinforcement 7, or its equivalent may be 45 employed with advantage.

To permit of applying the mounted specimens in various situations for decorative effect I also provide the body of the specimen with attaching means of some suitable sort as, for example, some suitable adhesive substance, as plastine, applied, as indicated at 8 in the drawing to the underside of the body of the specimen in order that the same may be caused to adhere to a vase, dish or the like, as indicated in Fig. 1, or if desired, a pin or coiled wire 9 may be attached at the underside of said body as indicated in Fig. 2 in order that the specimen may be applied in other situations, as to plants or 50 among cut flowers and the like.

In certain cases also, it may be desirable to employ a supplemental reinforcement or covering, as 10, applied over the upper or outer surfaces of the wings as indicated in Fig. 4 of the drawings. Such supplemental reinforcement or covering may be made from thin transparent gauze or other material so as not to detract from the distinctive markings of the wings, and may be attached only 55 around the edge portions thereof, to facilitate which the sheet reinforcing material 1 may be trimmed a short distance outside the margins of the wings so as to leave a narrow projecting edge portion, as indicated at 11 in Fig. 4 whereon the supplemental reinforcement 10 is secured in order to avoid damage to the upper or outer surfaces of the wings.

From the above description of my improvements it will be seen that the mounting embodying my invention is of an extremely simple and comparatively inexpensive nature, and is particularly well adapted for use by reason of the strength and durability afforded in the mounted or prepared specimens, enabling them to be subjected to any ordinary usage and handling without liability of damage or injury despite the essentially fragile and delicate character of the dried natural specimens, and it will also be obvious from the above description that the mounting is susceptible of some modification without material departure from the principles and spirit of the invention, and for this reason I do not desire to be understood as limiting myself to the precise formation and arrangement of the several parts as herein set forth in carrying out my invention in practice.

Having thus described my invention, what I claim and desire to secure by Letters Patent of the United States is:

1. A mounted specimen of the character described having wing reinforcements formed from thin resistant material extended across the surface of the wing structure at one side thereof to strengthen the same against injury without obliteration of the natural wing markings.
2. A mounted specimen of the character described having a body, and wing reinforcements at its opposite sides each formed from thin resistant material extended across the surface of the wing structure at one surface thereof to strengthen the same against injury without obliteration of the natural wing markings and affording secure attachment of the wing structure to the body of the specimen.
3. A mounted specimen of the character described having oppositely arranged similar wing structures each provided with a reinforcement extended across one of its surfaces to strengthen the structure without obliteration of the natural wing markings, and a body to which the respective wing structures are attached, capable of being bent to cause said wing structures to stand at desired angles.
4. A mounted specimen of the character described having oppositely arranged similar wing structures each provided with a reinforcement of thin resistant material ex-
- tended across one of its surfaces to strengthen 35 the structure without obliteration of the natural wing markings, and a body formed from two attached members between which the inner adjacent edge portions of the respective wing structures are held.
5. A mounted specimen of the character described having oppositely arranged similar wing structures each provided with a reinforcement of thin resistant material extended across one of its surfaces to strengthen 45 the structure without obliteration of the natural wing markings, and a body to which the respective wing structures are attached provided with an attached reinforcement capable of being bent to cause said wing structures to stand at desired angles.
6. A mounted specimen of the character described having oppositely arranged similar wing structures, and a body to which the respective wing structures are attached, ca- 55 pable of being bent to cause said wing structures to stand at desired angles.
7. A mounted specimen of the character described having oppositely arranged similar wing structures, and a body to which the 60 respective wing structures are attached provided with an attached reinforcement capable of being bent to cause said wing structures to stand at desired angles.

In witness whereof I have hereunto signed my name this 15th day of March, 1916.

THEOPHIL PFISTER.
